UNITED STATES PATENT OFFICE

GEORGE E. KARL, OF BEREAL, OHIO, ASSIGNOR TO THE DUNHAM COMPANY, OF BEREAL,
OHIO, A CORPORATION OF OHIO

DESIGN FOR A ROTARY HOE

Application filed January 27, 1930. Serial No. 34,298. Term of patent 14 years.

To all whom it may concern:

Be it known that I, GEORGE E. KARL, a citizen of the United States, residing at Berea, in the county of Cuyahoga and State of Ohio, have invented a new, original, and ornamental Design for Rotary Hoes, of which the following is a specification, reference being had to the accompanying drawing, forming a part thereof.

Fig. 1 is a plan view of a rotary hoe, showing my new design.

Fig. 2 is an elevational view of the same.

I claim:

The ornamental design for a rotary hoe substantially as shown.

GEORGE E. KARL.
